UNITED STATES PATENT OFFICE

2,650,731

TRANSPORTATION SYSTEM AND EQUIPMENT

William F. Adler, Pittsburgh, Pa.

Application April 8, 1947, Serial No. 740,062

1 Claim. (Cl. 214—515)

1

My invention relates to the transportation of parcels and goods, such as mail, baggage and express, by rail. Ordinarily such goods are shipped on trains having passenger cars as well as baggage and express cars; and the stopping time at stations, particularly intermediate stations, is generally determined by the loading and unloading time at present required for handling mail, baggage and express, which is usually much longer than the stopping time desirable for passenger service. My apparatus and system accomplish the unloading and loading of mail, baggage and express in a much shorter time, comparable to the short interval now prevailing for passenger trains not handling express, mail or baggage. The increment of time saved at each station is substantial, and the cumulative saving over a given route may permit it to be traveled in considerably shorter time. In the use and practice of my invention, the greater part of the labor heretofore performed while waiting at intermediate stops may be done while the train is in transit, and the actual labor to be performed while the train is stopped requires but a brief interval of time.

My apparatus consists of units of two cooperating kinds, each of the nature of a cart or truck, and the two kinds being differentiated according to their specialized and unique functions in the handling of goods shipped. All the units of the same kind are similar in construction and are interchangeably used with companion units of the other kind at different stations along the railroad employing my system. One of these kinds of units may be described as roller pallets or platforms, which are shallow carts for goods to be loaded or unloaded, and are carried between stations in the railway cars. The other or companion kind may be described as carriages, which are wheeled vehicles adapted to receive the roller pallets from the cars and to deliver other pallets to the cars. The carriages with pallets mounted thereon thus comprise baggage trucks which are operated at particular stations between the railway cars stopping there and the express and baggage rooms. Each carriage has a track frame of adjustable elevation, substantially at the height of the car floor above the station platform, on which are tracks of a gauge registering with the rollers on the pallets; and the two kinds of units are constructed to contact in use as to guide the transfer of pallets between the carriage and railway cars, and to retain the assembly against displacement in transit to and from the station express and baggage

facilities. In other words, my apparatus is a novel baggage truck having separable carriage and load platform, which is constructed to permit the platforms to glide horizontally into and out of an adjacent railroad car; and it thus provides alternately substantially rigid platform trucks at stations and shallow portable pallets for service within the railway cars between stations.

My system of transportation requires the use of pluralities of such carriages and roller pallets, in conjunction, of course, with railroad trains. The number of carriages required is approximately proportional to the number of stations along the route, plus spares and extras for peak service requirements; and the number of roller pallets is approximately proportional to the sum of the number of carriages and the number of baggage and express cars on the trains serving the route using my system. Each baggage and express car contains one or more roller pallets substantially all the time; and the carriages at the stations have one or more pallets mounted thereon substantially all the time. I contemplate providing more than one pallet per car and carriage, as, for example, two each, which is convenient with long, narrow carriages comparable to baggage trucks now in general use and with pallets of suitable length to pass readily through doors of express and baggage cars.

My system contemplates substantially the following steps in the rail transportation of goods. While the train is in transit approaching a station, goods to be unloaded at the station are deposited upon one or more pallets within the car; and at the station, goods to be loaded upon that car, if any, are deposited upon one or more carriage-mounted pallets. When the train arrives, the carriage is wheeled adjacent the car door, and pallets are exchanged from carriage to car and car to carriage, this exchange leaving unchanged the number of pallets in or on each vehicle. A loaded pallet is thus always exchanged for a different pallet, which may or may not be loaded also. Obviously, an empty pallet will be exchanged for a loaded one whenever goods are to be loaded only or unloaded only at some particular stop. This exchange requires a very brief time, and the railway car is quickly ready for departure. Subsequently, goods received may be stowed away in the railway car and the pallet may be leisurely loaded with goods destined for delivery at the next station.

I prefer to equip the pallets with handle rails at each end, which are hinged to the platform to fold flat when the pallet is not in use so that

it may be set aside and take up little space within a railway car. The pallets also are preferably provided with a manual or pedal-operated braking device to prevent undesired rolling about in the car. They may be conveniently fabricated of metal sheets, flanged around the circumference and ribbed for strength; and roll on shallow ball casters. Each pallet also includes a guiding means disposed on its under side which is formed to engage a guide receiver on the carriage, and to drift the pallet into entry position with respect to the carriage tracks.

The carriages each include a car frame on which the wheels are mounted and a track frame connected thereto through an intermediate jacking device whereby the level of the track frame can be adjusted to registry with the railway car floor. Hinged to the track frame are gates which when raised confine the pallets between ends of the tracks, and when lowered bridge the gap between the carriage and the railway car. Latches are preferably provided to secure the gates in raised position. As previously mentioned, the carriages may conveniently be made of sufficient length to bear two pallets disposed end to end. Mounted on the track frame I also provide the above mentioned pallet guide receivers, which are constructed to diverge or spread on the side adjacent the car to permit easy entry of the guiding means depending from the pallet.

A complete understanding of my apparatus and system may be obtained from the following detailed description and explanation with reference to the accompanying drawings illustrating one example. In the drawings,

Figure 1 is a plan view of my apparatus at the door of a railway car, which is shown partially in section;

Figure 2 is an end elevation of my apparatus with a portion of the railway car indicated in section;

Figure 3 is side elevation of a carriage;

Figure 4 is a sectional elevation taken on the line IV—IV of Figure 1;

Figures 5 and 6 are partial vertical sections through the carriage at the lines V—V and VI—VI respectively in Figure 4, but to a larger scale than Figure 4;

Figures 7 and 8 are horizontal projections of certain parts viewed as indicated by the section lines VII—VII and VIII—VIII in Figure 4, other parts being omitted for clarity; and

Figure 9 is a longitudinal vertical section on the center line of the frame, showing a portion of the jack mechanism at the line IX—IX of Figure 4, but to larger scale; the shaft and gearing not being shown in section.

Referring first particularly to Figures 1, 2, and 3, two roller pallets 1 are shown, one entirely on the carriage 2 and the other partially on the carriage and partially within an adjacent railway car. Each pallet is comprised of a shallow platform tray 3 which rolls on four ball rollers or casters 4, two folding handles 5 (not shown in Figure 1 for clarity), depending guide rail 6, and brakes 7. The pallets have a length which is conveniently entered through the door of the railway car and a width slightly less than the width of the carriage 2. The carriage is shown disposed on the station platform laterally adjacent a railway car, with substantially half its length beside the car door. It is comprised of a lower frame 8 resting on rear wheels 9 and front steering wheels 10 through conventional intermediate members in any manner known to the

art, and an upper or track frame 11 supported from the lower frame 8 through intermediate adjustable means presently to be described in detail. Hinged to the two sides of track frame 11 are four gates 12, two being on each side. Three of the gates are shown in raised position, the fourth being lowered to rest at its extremity on the floor of the railway car through the door, so as to provide a bridge for passage of the roller pallet between the car and the carriage. The gates in raised position are secured by latches 13, to confine the pallets laterally on the carriage. Extending across the frame 11 between the gates 12, are four parallel trackways 14, comprising two pairs, each of which accommodates the casters 4 of one pallet in proper assembled position on the carriage. Mounted on the frame 11, adjacent the gates 12 and substantially midway between the two trackways 14 provided for each pallet, are pairs of guide-receiving rollers 15 which engage the depending rail 6 of the pallets from opposite sides and center the casters 4 in the trackways. Four such pairs of rollers 15 are provided on a two-pallet carriage.

Referring now principally to Figure 4 and the auxiliary small detail figures, the upper or track frame 11 is comprised of a pair of longitudinal stringers 16 which are conveniently channel-shaped in section with a horizontal web and deep downstanding flanges, across which are secured end beams 17 and center beam 18. The beams 17 and 18 are wide-webbed inverted channels pressed of metal plate, and the trackways 14 are depressions formed in the horizontal webs thereof, there being two such depressions in the center beam 18 and one each in the end beams 17. The depending flanges of the beams 17 and 18 are framed into the stringers 16, and extend beyond to the edge of the carriage; and the gates 12 are hinged thereto by means of hinge plates 19 (see Figures 3 and 6), except at the extreme ends of the frame, where the depending flanges of beams 17 provide a support for the pivots 20 for the latches 13. The guide rollers 15 are spaced apart horizontally above the stringers 16 and turn about pivot pins 21 which are retained in anchor blocks 22 secured between the flanges of the stringers (see Figure 5).

Extending horizontally through each stringer 16, and bearing in blocks 23 confined therein, are three supporting pivot pins 24, one being substantially at the center of the stringer and the other two being near the ends thereof. The ends of these pins rest in bearings at the upper ends of the inclined links 25, 26 and 27; the two end links 25 each being pivoted at the ends of the stringers and the center links 26 and 27 being pivoted about opposite ends of the pins 24 at the centers of the stringers. The lower ends of the links bear on trunnion journals 28 projecting laterally from jack nuts 29, which rest on slide rails 30 secured in lower frame 8 and are movable therealong by turning the jack screws 31 on which the nuts 29 are threaded.

The end links 25 are each comprised of welded bars and plates, to form, as best shown in Figure 7, a rectangular structure having yokes 32 and 33 at the corners which embrace the stringers 16 at the top and the nuts 29 at the bottom, which yokes are bored to receive the pivot pins 24 and trunnion journals 28. The center links 26 and 27, as shown particularly in Figures 6 and 8, are similar rectangular structures provided with yokes 33 at the bottom to receive their jack nuts 29, but have single bearing brackets 34 at the top

adjacent opposite sides of the stringers 16, the brackets of link 26 being on the inside of the stringers and those of link 27 being on the outside, to bear on opposite ends of the pin 24 at the center of the stringers.

The lower frame 8 of the carriage is comprised of two longitudinal side beams 35, transverse end beams 36, and spaced center cross beams 37. The jack screws 31 are journalled at their ends to turn in bored bearing blocks 38 welded to the webs of beams 36 and 37. Rails 30 along which the nuts 29 glide are framed between the beams 36 and 37 below the screws 31; and may conveniently be formed integral with the side beams 35 as shown in Figure 6. The jack screws 31 are threaded between journals with right hand threads on one side and left hand threads on the other side of their center, and the nuts 29 are threaded to match, so as to move in opposite directions along each screw when it is turned. To the ends of the screws between the beams 37, bevel gears 39 are secured, forming opposed pairs, each gear meshing with one of the two bevel gears 40 which are secured to the transverse operating shaft 41, best shown in Figure 9. This shaft is journalled at each end in bearing blocks 42 welded to the webs of side beams 35 substantially at their centers. The ends of shaft 41 extend through the beams 35, and are shaped to receive a fixed or removable crank handle 43. Rotation of shaft 41 by turning the crank 43 turns all the bevel gears and the four jack screws, causing the nuts 29 to glide along the rails 30, and lifting or lowering the upper frame 11 by varying the inclination of the links 25, 26 and 27. It will be evident that this provides substantial adjustment of the level of the track frame of the carriage to accommodate the platform arrangements of different stations and the use of different cars over the route. For extreme conditions, special carriages may of course be provided; and my apparatus and system are not limited to uniformity of equipment throughout, but any reasonable means of handling the pallets may be provided where the preferred form of carriages is not suitable.

The wheel mounting of the carriage may be any convenient arrangement which it is not necessary to describe here in detail; it being sufficient to note that the wheels 9 are mounted on a fixed axle 44 extending between brackets 45 depending from the frame 8, and the wheels 10 are mounted on a pivoted axle 46 turning about a king pin 47 in a bridge 48 which spans the frame 8 at the steering end; the car being pulled by drawbar 49 pivoted to the axle 46.

The pallets are preferably light, shallow and strong and the horizontal platform 3 may be reinforced with ribs for stiffness. To hold them stationary when rolling is not desired, suitable braking means is provided, which may be any suitable device. One such device is indicated at 7, which is constructed after the fashion of a conventional pedal depressed, spring released door check, a well-known article of hardware, which when depressed constitutes a retractable

support independent of the rollers 4. Preferably, the guide rail 6 of the pallet diverges towards the bottom, and the guide-receiving rollers 15 have beveled engaging surfaces which overlap 5 the diverging rail head to confine the pallet from vertical as well as longitudinal displacement, as best shown in Figure 4. In other words, the guide rails and rollers interlock both vertically and longitudinally, due to the oppositely beveled 10 engaging surfaces. The handles 5 are pivoted on brackets 50 secured to the platform 3, and are foldable against the platform when it is desired to set them aside when not in use.

Although I have illustrated and described but 15 one embodiment of my apparatus and system, changes in details of construction and modification of the arrangement disclosed may, of course, be made without departing from the spirit of the invention or the scope of the appended claim. 20 While the invention has been particularly described with reference to shipping by rail, it may be applied as well to other uses, such as distribution of parts in process of manufacture in factories, deliveries other than by rail, and the like; and permanent or removable side walls and lids may obviously be added to the pallets, or other changes made, to suit handling of goods in containers instead of open platforms where this 25 appears desirable.

30 I claim:

A baggage cart comprising a wheeled carriage having a plurality of generally horizontal trackways extending transversely of said cart, a plurality of platforms comprising collectively the 35 deck of said cart, rollers on each of said platforms engaging one of said trackways, a transverse guide rail extending beyond and intermediate said rollers and depending from said platform, and generally horizontal rollers mounted in pairs on each side of said carriage, said rail and said horizontal rollers having bevelled 40 engaging faces in interlocking relation adapted to drift the platforms entering said trackways to centered position therein and to restrain said platforms from vertical displacement with respect to said carriage.

45 WILLIAM F. ADLER.
